Primary Examiner — Susan E Krakower*Assistant Examiner* — Jerry Shiuan-Hua Hsu(74) *Attorney, Agent, or Firm* — Zhihua Han; Wen IP LLC(57) **CLAIM**

The ornamental design for a foot pedal, as shown and described.

DESCRIPTION

FIG. 1 is a perspective view of a foot pedal showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines illustrate portions of the foot pedal that form no part of the claimed design.
